UNITED STATES PATENT OFFICE.

HENRY BRUCKER, OF NEWARK, NEW JERSEY, ASSIGNOR TO AMERICAN ALUMINUM WARE COMPANY, A CORPORATION OF NEW JERSEY.

SEAMED TUBE.

Application filed November 20, 1925. Serial No. 70,411.

This invention relates in general to seamed tubes, that is tubes made of sheet metal the edges of which are seamed together, and more particularly the invention relates to such a tube especially designed for use as a core for a coil of tape, ribbon and the like.

One object of the invention is to provide a seamed tube formed of one piece of sheet metal and having a novel and improved mechanical interlocking connection or seaming together of the edges thereof to hold the sheet in tubular form.

Another object is to provide such a tube formed of a single sheet of material and having its longitudinal edges provided with novel and improved ears or projections to form an interlocking connection of the edges to hold the sheet in tubular form, whereby the edges may be interlocked as the sheet is rolled into the form of a tube and in one operation.

Further objects are to provide a tube of this character which is simple and inexpensive in construction; to provide a tube of this character in which the seam or connection of the edges of the sheet of material produces no material projection from the periphery or surface of the tube, and to obtain other results and advantages as may be brought out by the following description.

Referring to the accompanying drawing, in which corresponding and like parts are designated throughout the several views by the same reference characters,

Figure 1 is a side elevation of a tube embodying the invention, viewing the same from the seamed side thereof;

Figure 2 is a vertical longitudinal sectional view, taken on the line 2—2 of Figure 1;

Figure 3 is a side elevation of the tube viewed from an angle of 180 degrees to that of Figure 1;

Figure 4 is a transverse vertical sectional view, taken on the line 4—4 of Figure 1, and

Figure 5 is a plan view on reduced scale of the blank sheet of material from which the tube is formed.

Specifically describing the illustrated embodiment of the invention, the reference character A designates a substantially rectangular sheet of suitable material, for instance aluminum, which is provided on its longitudinal edges 1 with a plurality of in-

tegral projections or ears 2 which may be formed in any suitable manner as by a stamping operation. The ears 2 at one edge of the sheet are arranged in alternate or staggered relation to the ears at the other edge of the sheet, and preferably the ears are in general arcuate in configuration but have straight portions 3 at their bases arranged at substantially right angles to the corresponding edge of the sheet A. All of the ears 2 are of the same size and arranged with the straight portion 3 of an ear at one edge of the sheet in substantial alinement with the straight portion of an ear at the other edge of the sheet, as clearly shown in Figure 5 of the drawings.

To form a tube from the sheet A, the sheet is rolled in any suitable known manner into tubular form so as to cause the ears 2 at one edge 1 to overlap the opposite edge, as shown in Figures 1 and 4, and at the same time the ears are pressed downwardly against the sheet. In this operation, the straight portions 3 of the ears at one edge of the sheet are brought into abutting relation with the corresponding sides 3 of the ears at the other edge of the sheet, and the operation is performed with some force so that a slight jamming action takes place at the angles formed by the meeting of the straight portions 3 of the ears with the edges 1 of the sheet A.

With such a construction, the curvature of the ears corresponding to the curvature of the tube, as shown in Figure 4, in connection with the jamming action produced by the straight sides 3 of the ears, prevents the edges of the sheet from separating in a circumferential direction; the alternate overlapping relation of the ears and the opposite edges of the sheet prevents the edges of the sheet from being pressed inwardly of the tube or expanded outwardly. Furthermore, the overlapping relation of the ears 2 and the edges 1 of the sheet, the corresponding arcuate curvature of the ears and the tube and the pressing of the ears into the opposite edges of the sheet, eliminate all projections on the exterior surface of the tube. The edges of the sheet may be secured together as above described in one operation and without any bending, twisting, soldering or other fastening operations common to many of the known seaming operations.

Preferably, the end edges of the sheet are

returned upon the sheet as at 4 to provide smooth ends for the tube and also to reinforce the end edges of the tube. Such a tube is particularly advantageous as a core for a coil of tape, ribbon, and the like, since it is cheap and may be discarded after use, and is sufficiently strong to withstand the winding operation and support the coil thereon.

The sheet may have stamped therein a rib 10 5 which will project inwardly of the tube, said rib serving as a key to enter the keyway of a winding mandrel or spindle so as to cause the tube to rotate with the spindle during the operation of winding tape or ribbon upon the tube. This rib 5 may be formed in the same stamping operation which produces the blank for forming the tube.

Obviously, the invention may be embodied in tubes for various purposes and of various sizes, as may be desired. Furthermore, the details of construction of the tube may be modified and changed by those skilled in the art without departing from the spirit or scope of the invention. Therefore, I do not desire to be understood as limiting myself except as required by the following claims when construed in the light of the prior art.

Having thus described the invention, what I claim is:

1. A seamed cylindrical tube comprising a single sheet of material having a plurality of integral ears in spaced relation at each longitudinal edge thereof with a portion of the straight edge of the sheet between adjacent ears, said ears at one edge being disposed in staggered relation to the ears on the other edge and each overlapping the opposite edge of said sheet and pressed thereinto with its outer surface in the same curved plane as the outer periphery of the tube, each of said ears having a substantially straight portion at each side thereof meet-

ing the corresponding edge of said sheet at 45 substantially right angles and in abutting relation to corresponding portions of an ear at the opposite edge of said sheet, the edges of said sheet at the bases of said ears being also in abutting relation. 50

2. A seamed cylindrical tube comprising a single sheet of material having a plurality of integral substantially convexly arcuate ears in spaced relation at each longitudinal edge thereof with the straight edge of the sheet between them, said ears at one edge being disposed in staggered relation to the ears at the opposite edge and each ear overlapping the opposite edge of said sheet and conforming circumferentially to the curvature of the periphery of the tube, the arcuate formation of the ears permitting the edges to smoothly conform to the circumferential curvature of the tube. 55

3. A blank for a seamed cylindrical tube comprising a single sheet of pliable material having a plurality of identical integral ears in spaced relation at each longitudinal edge thereof with the straight edge of the sheet between them, said ears having 70 straight portions on their sides at their bases meeting the corresponding edge of said sheet at substantially right angles and having convexly curved outer ends, said ears at one edge being disposed in staggered relation to 75 the ears at the opposite edge, so that when said blank is compressed circumferentially each ear overlaps the opposite edge of and is pressed into said sheet so as to conform to the curvature of the periphery of the tube, the 80 straight portion of each of said ears being jammed into an abutting relation with the corresponding portion of the adjacent ear at the opposite edge of said sheet and the edges of said sheet between said ears being 85 jammed into an abutting relation at the bases of said ears.

HENRY BRUCKER.
